UNITED STATES PATENT OFFICE

143,060

DESIGN FOR A REFRIGERATOR PANEL

William S. Connell, Norwood Park Township,
Cook County, Ill., assignor to The Bastian-Blessing Company, Chicago, Ill., a corporation of Illinois

Application December 2, 1944, Serial No. 116,673

Term of patent 7 years

(Cl. D67—3)

To all whom it may concern:

Be it known that I, William S. Connell, a citizen of the United States, residing in Norwood Park Township, in the county of Cook and State of Illinois, have invented a new, original, and ornamental Design for a Refrigerator Panel, of which the following is a specification, reference being had to the accompanying drawing, forming part thereof.

Fig. 1 is a front elevational view of the refrigerator panel showing my new design.

Fig. 2 is a side elevational view, and
Fig. 3 is a top plan view thereof.

I claim:

The ornamental design for a refrigerator panel,
as shown.

WILLIAM S. CONNELL.
